ASSEMBLING ELEVATOR CONTROL DEVICE FOR
A TYPOGRAPHICAL COMPOSING MACHINE

Louis Rossetto, Kings Point, N. Y., assignor to Mergenthaler Linotype Company, a corporation of New York

Application March 31, 1958, Serial No. 724,961

4 Claims. (Cl. 199—18)

This invention relates to typographical composing machines of the general organization represented in U. S. Letters Patent to O. Mergenthaler, No. 436,532, wherein circulating matrices and spacebands are composed in line in an assembling elevator by the operation of a keyboard, the elevator raised to line transfer position, the composed line transferred therefrom to a "first" elevator which presents the line, between a pair of vise jaws, to the face of a mold for the casting of a type bar or slug, and the matrices and spacebands thereafter separated and returned to their places of storage. More particularly, the invention relates to machines of that class adapted to be equipped with an automatic control unit, such as a Teletypesetter Unit, which automatically operates the keyboard and raises the assembling elevator in response to code perforations in a tape.

In these machines, line composition and casting is completely automatic, making it unnecessary for an operator to sit at a keyboard, as in the conventional method of composition. Since supervision of the machine is at a minimum during operation, any failure of delivery of matrices or spacebands to the assembling elevator in response to signals in the tape will not be detected immediately. Inasmuch as no operator is present to notice and correct such a deficiency while the line is in the assembling elevator, any incomplete line assembled on the elevator will be interposed between the vise jaws and presented to the mold. As usual, the line is then justified, that is to say, the wedge-shaped spacebands in the line are driven upwardly, expanding the line between the jaws. Thereupon, the molten metal is forced into the mold and against the line under considerable pressure. If, upon justification, the composed line is not fully expanded between the vise jaws, due to either the failure of delivery of one or more matrices to the assembling elevator, making the line unduly short, or the failure of delivery of the proper number of spacebands to the assembling elevator, the casting mechanism will be automatically rendered inoperative, in a well known manner, in order to prevent liquid metal from being forced through any spaces or openings in the line. However, in spite of the fact that all the matrices and spacebands called for on the tape have not been delivered and hence are not included in the composed line, it frequently happens that the line will still be fully expanded between the vise jaws and, of course, an erroneous slug will be cast. It is only after the casting operation that the deficiency will be observed, if in fact it is noticed at all, and the line will then have to be recomposed and recast.

The present invention is intended to obviate the above difficulty by equipping automatically operated machines with a means which automatically prevents the raising of the assembling elevator when the failure of a matrix or spaceband to be delivered in accordance with the operation of the keyboard is detected. The invention accomplishes this purpose by counting the number of signals in the tape calling for matrices and spacebands, and comparing that to the number of matrices and space-

2

bands actually delivered to the assembling elevator. If the two totals do not correspond, the elevator is positively prevented from rising. This, of course, causes no damage to the machine since, as is well known, the elevator raising mechanism automatically slips when its motion is obstructed. If the two totals do correspond, the locking mechanism is rendered inoperative, and the elevator is allowed to rise to its line delivery position.

The details of the present invention will be more fully described in the specification which follows.

In the drawings:

Fig. 1 is a side elevational cross-sectional view taken through the keyboard and matrix release mechanism of a composing machine showing the matrix signal device;

Fig. 2 is a front elevational view of the assembling entrance and elevator showing the matrix response device;

Fig. 3 is a perspective view of a spaceband box showing the spaceband signal device;

Fig. 4 is a cross-sectional view on line 4—4 of Fig. 3 showing the spaceband response device;

Fig. 5 is a side elevational cross-sectional view of the assembling elevator raising mechanism of an automatic control unit;

Fig. 6 is a detail perspective view of the matrix signal device;

Fig. 7 is a perspective view of the end-of-line switch and its operating cam; and

Fig. 8 is a schematic circuit arrangement of the invention.

Referring to the drawings, particularly Fig. 1, a typographical linccasting machine is operated automatically by a Teletypesetter control unit 10. As usual, the Teletypesetter unit 10 serves to selectively depress the keylevers 11 of the composing machine in accordance with the signals in a perforated tape 17 which is fed into the unit. Conventionally, when a keylever 11 is depressed, a keyboard bar 12 is raised, rotating trigger 13 about rod 14. This releases a cam yoke 15, pivoted at 16, which drops and allows a cam 19, rotatably mounted between the tines of the yoke 15, to contact a continuously rotating rubber roller 20. Roller 20 serves to rotate cam 19, which, by virtue of its eccentricity, raises yoke 15 until the free end thereof strikes and lifts key reed 21, which in turn lifts long key rod 22. Rod 22 rotates escapement lever 23, pivoted at 24, thereby activating the escapement mechanism which releases a matrix 25 from the magazine 26. The matrix 25 then falls through chute 29 on to a delivery belt 30 which delivers it, for composition in line, to an assembling elevator 31, the line thereafter being presented to a mold wherein a typographical slug is cast.

The above description is, of course, familiar to those in the typographical composing art.

In the present invention, the reactions of the matrix and spaceband release mechanisms to the operation of the Teletypesetter control unit are employed to count the matrix and spaceband signals on the perforated tape, i. e. to count the number of times that the keyboard is operated. On the other hand, matrices and spacebands themselves are utilized to record their own delivery to the assembling elevator.

The manner in which a matrix signal on the tape 17 is detected may be seen in Fig. 1 and more clearly in Fig. 6. A supporting bracket 32 is mounted on the machine frame 33. A narrow plate 34 whose length slightly exceeds the distance between the extreme members of the long key rod bank 22, is pivotally mounted about one long edge in bracket 32. Each long key rod 22 is provided with a slot 35 in its machineward edge, the lower wall of which is parallel to the line about which plate 34 is pivoted. Therefore, when plate 34 is in its normal position, resting on the lower walls of slots 35, it will be disposed perpendicular to the bracket

32. The matrix signal switch 36 is mounted on bracket 32 above the pivoted plate 34. The lower contact 39 of switch 36, which is normally open, is provided with a roller 40 which rests on the upper surface of plate 34.

As is well known, there is one long key rod 22 associated with each key lever 11. Therefore, each time a tape signal operates a key lever 11, a long key rod 22 is raised, indicated by the arrow in Fig. 6, pivoting plate 34 upward. When this occurs, roller 40 rides on the upper surface of plate 34 as lower contact 39 of switch 36 moves upward to close the switch. The switch then opens as the long key rod 22 returns to its normal position. It should be noted that the slots 35 are cut high enough to allow one long key rod to rise while the others remain inert, thus permitting independent action of each long key rod.

For our purposes herein, the spaceband release mechanism operates in much the same way as the matrix release mechanism, in that a vertical link 41 (Fig. 4) is lifted in response to operation of a key lever (not shown). The raising and lowering of vertical link 41 serves to actuate the spaceband escapement mechanism through spaceband escapement lever 42, thereby releasing a spaceband 43 from spaceband box 44. The vertical link 41 is provided on one side with a lug 47. The spaceband signal switch 45, mounted on a bracket 46, is provided with two thin wire contacts 49 and 50, arranged one above the other, and disposed in the path of lug 47 on link 41. Consequently, when a spaceband is called for on the tape, vertical link 41 will rise and lug 47 will lift lower contact 50 into engagement with upper contact 49, thereby closing the spaceband signal switch 45.

As was mentioned before, the matrices and spacebands activate the response switches as they are being delivered. The matrix response device will be described with reference to Fig. 2 in which matrices 25 are shown being carried by delivery belt 30 to an inclined chute 51, through which the matrices 25 fall on to assembling elevator 31. A bell crank 52, is pivotally mounted at 53 on the machine frame directly above the chute 51, in place of the usual chute spring. The lower finger of bell crank 52 is biased into contact with chute 51 by a light tension spring 54 positioned between the machine frame and the upper finger of the bell crank. The matrix response switch 55, mounted on the machine frame, is provided with two externally projecting contact strips 56 and 57, which are normally separated. As a matrix leaves the delivery belt 30 and falls through the inclined chute 51, it will pivot bell crank 52 clockwise through a small angle. This movement is sufficient to permit the upper finger of the bell crank to move one contact strip 57 of switch 55 into engagement with the other contact strip 56, thus signaling delivery of a matrix. The contact will then be broken immediately as spring 54 returns bell crank 52 to its normal position, contacting chute 51.

The spaceband response switch is disposed in the lower extremity of the spaceband delivery channel 60, which depends from the spaceband box 44, and through which a spaceband being delivered to the assembling elevator must fall. Referring to Fig. 4, one flexible contact strip 62 of spaceband response switch 61 is disposed just out of the path of the falling spaceband, while the other flexible contact strip 63 is so positioned that the distance between it and the far wall of the channel 60 is less than the width of the spaceband 43 at its widest point. Therefore, as the spaceband falls past the position of the contacts, it pushes contact strip 63 into engagement with contact strip 62, thereby signaling its delivery.

When a completed line of matrices and spacebands has been composed on the assembling elevator 31 an elevator operating signal or end-of-line signal in the tape is sent through the Teletypesetter unit, which serves to arrest further movement of the tape and to activate the

elevator raising mechanism of the Teletypesetter shown in Fig. 5. A Y-shaped elevator shaft arm 64, rotatably mounted on elevator operating shaft 65, has a follower roller 66 at the extremity of one bifurcation, and a spring loaded detent 69 projecting from the end of the other bifurcation. The follower roller 66 rides on the elevator cam 70 which is mounted on the elevator power shaft 71. The tapered end of detent 69 is normally disposed in a notch 72 in a segment member 73 which is fixed on elevator operating shaft 65. The above mentioned elevator operating signal effects a rotation of elevator power shaft 71, and hence elevator cam 70, through one complete revolution. This serves to pivot elevator shaft arm 64 in a counter-clockwise direction which in turn pivots segment member 73 through the driving connection between detent 69 and notch 72, thereby pivoting shaft 65 which raises the assembling elevator. As is well known, should there for any reason be an undue resistance to the movement of the assembling elevator, spring loaded detent 69 will yield, come out of engagement with notch 72 and ride in a trackway 74 of segment member 73. Consequently, even though shaft 71 continues to rotate when the elevator is unable to rise, no damage will be done to the machine.

As part of the present invention, in Figs. 5 and 7, a cam 75 is mounted on shaft 71, in addition to cam 70. An end-of-line switch 76, mounted on the machine frame directly above cam 75, is provided with two flexible contact strips 79 and 80 projecting horizontally therefrom. During the one revolution of shaft 71, cam 75 serves to close and open switch 76 once, for a purpose to be hereinafter described.

Referring to Fig. 2, the assembling elevator 31 is provided with a detent 81 projecting horizontally from its lower portion. A solenoid 82 is mounted on the machine frame, to the right of the detent 81, with its armature shaft 83, in deenergized position, disposed directly above detent 81. A normally closed elevator switch 84 is mounted on the machine frame above solenoid 82. One contact of switch 84 has a roller 85 mounted thereon, which engages a cam surface 86 disposed on the elevator 31 above detent 81. With this arrangement, as the elevator 31 rises, cam surface 86 opens elevator switch 84.

As mentioned before, when the end-of-line signal is sent through the Teletypesetter unit, cam 75 rotates through one revolution actuating the end-of-line switch 76. If a matrix or spaceband has been delivered for every matrix and spaceband called for on the tape 17, a circuit will be completed which energizes solenoid 82 serving to pull armature shaft 83 out of the path of detent 81, thereby allowing assembling elevator 31 to rise. As the elevator rises, it opens switch 84 which deenergizes solenoid 82, readying it for the next cycle. The fact that armature shaft 83 is disposed in its extended position will not hinder the return movement of the assembling elevator, after it has delivered the composed line, due to the oppositely beveled ends on detent 81 and shaft 83 which cooperate to allow the detent to slide the spring biased armature shaft out of its path.

If there has not been a response to every matrix and spaceband signal on the tape 17, the circuit which energizes solenoid 82 will not be completed, hence armature shaft 83 will not be moved out of the path of detent 81, and elevator 31 will not be allowed to rise. No damage will result to the machine due to this intentional "jamming" of the elevator, since the elevator raising mechanism of the teletypesetter automatically slips when the elevator is prevented from rising as was above described.

70 A warning light is thereupon automatically activated which attracts an attendant who may complete the line manually and set the machine in motion once again. Fig. 8 shows the electrical circuits employed to carry out the operation of the invention as hereinbefore described. The circuits are shown in a "straight" or "across-

the-line" form in which the contacts of a relay are shown separated from the relay coil which operates them and arranged in the circuits which they control. Thus it is possible to arrange each coil circuit in a "straight" line between parallel lines representing the power source.

In the across-the-line diagram the following relays will be found:

RSH—response stepper switch homing relay.

SSH—signal stepper switch homing relay.

EA—elevator activating relay.

WA—warning relay.

Throughout the description which follows, these letters will be applied to the coils of the above designated relays. Also, with reference numerals appended thereto, they will be applied to the contacts of these relays. The relay contacts are shown in deenergized condition.

In addition to the switches heretofore mentioned in the specification, the following mechanically actuated switches are also located in the across-the-line diagram.

RH—reset homing switch.

RS—restart switch.

The following stepping switches are also employed in the electrical system:

SSS—matrix and spaceband signal stepping switch.

RSS—matrix and spaceband response stepping switch.

The electrical circuits are connected to a source of power by switch means, not shown. Thereafter, when a matrix is called for on the tape, the matrix signal switch 36 closes completing a circuit from line W1, through switch 36 and stepper switch coil SSS to line W2. As the tape continues to feed through the automatic control unit, switch 36 opens, breaking the circuit. The make and break of the circuit serves to energize and deenergize the coil SSS and results in the advancement of brush SSS1 from its home position to the next adjacent contact of the stepper switch. Movement of brush SSS1 from its home position closes contacts SSS2, which remain closed as long as the stepper switch SSS is not in its home position, and open only when the stepper switch SSS returns to its home position.

In a similar manner, when a spaceband is called for on the tape, the spaceband signal switch 45 closes, completing a circuit from line W1, through switch 45 and stepper switch coil SSS to line W2. The circuit is broken when switch 45 opens, at which time brush SSS1 advances to the next adjacent contact.

In this way, each time a matrix or a spaceband is called for on the tape, brush SSS1 advances one contact.

When a matrix is delivered to the assembling elevator in response to a signal on the tape, the matrix response switch 55 closes completing a circuit from line W1 through switch 55 and stepper switch coil RSS to line W2. Coil RSS is thereby activated and causes brush RSS1 to move from its home position, shown in the diagram, to the next adjacent contact of the stepper switch, as was described previously with reference to the closing of switch 36. When stepper switch RSS is not in its home position, contacts RSS2 close, and open again only when the stepper switch RSS returns to its home position.

Similarly, when a spaceband is delivered to the assembling elevator in response to a signal on the tape, the spaceband response switch 61 closes completing a circuit from line W1 through switch 61 and stepper switch coil RSS to line W2. The circuit is broken when switch 61 opens, and brush RSS1 advances to the next adjacent contact.

Here, too, each time a matrix or spaceband is delivered to the assembling elevator, stepper switch RSS advances one contact.

It follows then, that if there has been a matrix and

spaceband response to every signal on the tape calling for a matrix or spaceband, brushes SSS1 and RSS1 will be disposed on corresponding contacts of their respective stepper switches when a complete line has been composed on the assembling elevator. As can be seen in Fig. 8, corresponding contact points on stepper switches SSS and RSS are directly connected to one another. Consequently, if a complete line has been composed, when the end-of-line switch 76 closes, a circuit is completed from line W1 through switch 76, stepper switches SSS and RSS, and elevator activating coil EA to line W2.

Energization of coil EA serves to close contacts EA1, completing a self-holding circuit from line W1 through elevator switch 84, contacts EA1 and coil EA to line W2. Contacts EA2 also close when coil EA is energized, completing a circuit from line W1 through solenoid 82 and contacts EA2 to line W2. Solenoid 82 is thereby energized moving the armature shaft 83 of solenoid 82 out of the path of detent 81, allowing the assembling elevator 31 to rise. Due to the energization of coil EA, contacts EA3 open, for a purpose to be hereinafter described.

As the assembling elevator rises, it opens elevator switch 84 which deenergizes coil EA. Contacts EA2 open deenergizing solenoid 82, allowing the armature shaft to return to its normal position, awaiting the next cycle.

When solenoid 82 is energized, reset homing switch RH closes, completing two circuits. One circuit is completed from line W1 through switch RH, contacts RSH2, and response stepper switch homing coil RSH to line W2, thereby energizing coil RSH. The other circuit is completed from line W1 through switch RH, contacts SSH2 and signal stepper switch homing coil SSH to line W2, thereby energizing coil SSH. When coil RSH is energized, contacts RSH1 close, completing a self-holding circuit from line W1 through contacts RSS2, which are closed since stepper switch RSS is not in its home position, RSH1 and coil RSH to line W2, after which contacts RSH2 open. Similarly, when coil SSH is energized, contacts SSH1 close completing a self-holding circuit from line W1 through contacts SSS2, contacts SSH1, and coil SSH to line W2, after which contacts SSH2 open.

Energization of coils RSH and SSH serve to advance stepper switches RSS and SSS respectively to their home positions, ready for the next cycle to commence, i. e. ready for composition of the next line to begin. When coil RSH is energized, contacts RSH3 close completing a circuit from line W1 through contacts RSH3, interrupter contact 90 and coil RSS to line W2, thereby energizing coil RSS similar to the manner in which matrices and spacebands being delivered to the assembling elevator, energized the coil. As soon as the circuit energizing coil RSS is complete, however, interrupter contacts 90 open, breaking the circuit and deenergizing coil RSS. As before, this make and break of the circuit serves to advance brush RSS1 to the next adjacent contact of the stepper switch. As soon as the circuit breaks, interrupter contacts 90 reclose, energizing coil RSS once again. When the interrupter contacts reopen, brush RSS1 will, of course, advance another step. The energizing and deenergizing of coil RSS will continue until brush RSS1 reaches its home position. At that time, contacts RSS2 will open, as mentioned before, deenergizing coil RSH, hence opening contacts RSH3. Thus when the stepper switch RSS reaches its home position, it will remain there until matrices and spacebands are again delivered to the assembling elevator.

In exactly the same manner as just described, coil SSH is energized, serving to close contacts SSH3, completing a circuit from line W1 through contacts SSH3, interrupter 91 and coil SSS to line W2. By means of interrupter 91 stepper switch SSS is returned to its home position, whereupon contacts SSS2 open, deenergizing coil SSH. The arrangement is now ready to repeat the above described cycle.

Assuming that one or more matrices or spacebands called for on the tape are not delivered to the assembling elevator, an incomplete line will be composed and brushes SSS1 and RSS1 will not be disposed on corresponding contacts of their respective stepper switches, when the end of line signal on the tape calls for the closing of switch 76. This is so since coil RSS will not have been energized as many times as coil SSS. Consequently, closing of switch 76 will not result in an energization of coil EA, hence contacts EA2 will not close and solenoid 82 will not be energized. Therefore, armature shaft 83 will remain in the path of detent 81, and the assembling elevator will be prevented from rising, when the tape signals for the elevator rise. As was mentioned before, movement of the tape is arrested as well.

Since coil EA has not been energized, contacts EA3 will remain closed, meaning that when switch 76 closes a circuit is completed from line W1 through switch 76, contacts EA3 and time delay coil WA to line W2. Energization of coil WA results in the closing of contacts WA1, making the circuit self-holding, and results in the closing of contacts WA2 which completes a circuit from line W1 through contacts WA2 and warning light 92 to line W2. The energized warning light, indicating that there is an incomplete line on the assembling elevator, will attract an attendant who may complete the line by manually placing the missing matrices or spacebands in proper position. The attendant then pushes restart push button RS which completes a circuit from line W1 through push button RS and coil EA to line W2, thereby energizing coil EA and in turn energizing solenoid 82. Since the elevator will then be allowed to rise, the operator may manually raise the elevator to line transfer position, and thereafter return it to normal composing position, following which he may re-initiate movement of the tape.

Energization of solenoid 82 will cause switch RH to close, causing stepper switches SSS and RSS to return to their home positions as described above. Contacts EA3 open when coil EA is energized, hence the warning light 92 will go off. The machine will now continue to operate normally, as described above, until the attendant is once again called upon to complete an incomplete line.

The invention has been shown and described in preferred form only and by way of example, but many variations and modifications may be made therein and in its mode of application which will still be comprised within its spirit. It is understood, therefore, that the invention is not limited to any specific form or embodiment, except in so far as such limitations are specified in the appended claims.

What is claimed is:

1. In a typographical composing machine, the combination of a keyboard for releasing matrices and spacebands from their places of storage, an assembling elevator wherein the released matrices and spacebands are delivered one after another to form a composed line, an automatic control unit having mechanism for automatically operating the keyboard and mechanism for raising the assembling elevator, a lock which normally prevents the raising of said elevator, means for counting the number of times the keyboard is operated during composition of a line, means for counting the number of spacebands and matrices that are actually delivered to said elevator during composition of the same line, and means to ren-

der said lock inoperative when the number of times that the keyboard is operated equals the number of spacebands and matrices that are delivered to said elevator.

2. In a typographical composing machine, the combination of a keyboard, means responsive to the operation of said keyboard for releasing matrices from a storage magazine, means responsive to the operation of said keyboard for releasing spacebands from a storage box, an assembling elevator wherein the matrices and spacebands are composed in line, an automatic control unit having mechanism for automatically operating the keyboard and mechanism for raising the assembling elevator, means for counting the number of times the spaceband releasing means and the number of times the matrix releasing means are operated by said keyboard during the composition of a line, means for counting the number of spacebands and matrices that are delivered to said elevator during the composition of the same line, a lock which prevents the raising of the assembling elevator, and means to render said lock inoperative when the number of spacebands and matrices delivered into the assembling elevator equals the number of times the spaceband releasing mechanism and the matrix releasing mechanism are operated.

3. In a typographical composing machine, the combination of a keyboard having a plurality of key levers thereon, an assembling elevator wherein matrices and spacebands are composed in line, an automatic control unit having mechanism for automatically operating said keyboard and mechanism, including a rotatable shaft, for raising the assembling elevator, means responsive to the operation of said keyboard for releasing matrices from a storage magazine, said means including vertically disposed long key rods associated with said key levers, means responsive to the operation of said keyboard for releasing spacebands from a storage box, said means including a vertically disposed link associated with one of said key levers, means for counting the number of times the matrix releasing mechanisms are operated during composition of a line, said means comprising a switch, and means associated with the long key rods for activating said switch whenever the matrix releasing mechanism is operated, means for counting the number of times the spaceband releasing mechanism is operated during composition of the same line, said means comprising a switch, and means associated with the vertical link for activating said switch whenever the spaceband releasing mechanism is operated, means for counting the number of matrices that are actually delivered to said assembling elevator during composition of said line, said means comprising a switch and means operated by the falling matrix for activating said switch, means for counting the number of spacebands that are actually delivered to said assembling elevator during composition of the same line, said means comprising a switch activated by the falling spaceband, a lock which prevents the raising of the assembling elevator, and means to render said lock inoperative, including a cam disposed on said rotatable shaft, and a switch operated by said cam.

4. A combination according to claim 3, including an additional switch operated by the rising assembling elevator, said switch serving to render said lock re-operative.
